UNITED STATES PATENT OFFICE.

GEORGE CHAFFEY, OF MILDURA, VICTORIA.

AUTOMATIC WATER-METER.

SPECIFICATION forming part of Letters Patent No. 527,046, dated October 9, 1894.

Application filed August 12, 1893. Serial No. 482,958. (No model.)

To all whom it may concern:

Be it known that I, GEORGE CHAFFEY, consulting engineer, a subject of Her Majesty the Queen of the United Kingdom of Great Britain and Ireland, and a resident of Mildura, in the British Colony of Victoria, have invented a certain new and useful Automatic Water-Meter, the following being a specification of my invention.

This invention consists of an automatic water meter designed mainly for use in controlling and delivering automatically a predetermined head of water (four (4) inches or thereabout) that is to supply an irrigation channel such head being maintained no matter what head of water may be in the supply channel. This meter may also be employed in water channels generally.

The apparatus is essentially composed of a box having an inlet at one end controlled by a butterfly valve that is governed by a water balance lever and at the other end an outlet controlled by a slide, the inlet opening being larger in area than the outlet.

In the attached drawings I illustrate my automatic water meter.

Figure 1. is a plan and Fig. 2. a view of its front or delivery end; Fig. 3., a longitudinal section on the broken line a . of Fig. 1. and Fig. 4. a view of the inlet opening and showing the butterfly valve in its horizontal open position; Fig. 5., a part longitudinal section showing an alternative position for the inlet opening it being arranged in the floor of meter box.

A. is the meter box; B., the inlet opening; C., the outlet opening; D., the overflow pocket.

The inlet opening B is preferably located near the bottom of a cross plate A' at one end of the wooden meter box A and which end receives the supply of water from its source while the outlet opening C is formed in a cross plate A² at the other or delivery end of said box. C' is a slide plate fitted in grooves at top and bottom of said outlet opening, C² being a handle for the slide said handle projecting into the small upper pocket

A³. At one side of the said box is the pocket D within which a regulating pan D' is arranged and into which latter the water from the box flows over a sill a' of proper height when the water in the meter box rises to the height of the upper edge of the delivery opening C. Said regulating pan has a small outlet orifice d at its one end governed by an adjustable slide d' while the pan itself is suspended from one arm of a beam E whose knife edge bearings e are supported on the sides of the box and pocket at a¹, a². The other arm of the said beam E is at its end connected by a rod E' with the butterfly valve B'; also an adjustable balance weight E² is arranged on this end of beam.

Upon the upper edge of the outlet opening is an indicator so that the slide may be set to allow the desired volume of water to pass through. The whole apparatus may be closed in and locked to prevent its being tampered with.

The operation of the automatic water meter is as follows:—Water being admitted to the box through the inlet opening B the water if a sufficient volume is flowing will rise therein until it overflows over the sill a' to the regulating pan D' and which becoming weighted by its contained water, weighs down the beam E the rising of the other end of which closes the butterfly valve B' and so closes or partially closes for the time being the supply opening B to the meter box. Then the water gradually runs from the pan D' through its outlet orifice d and the beam E again assumes its normal horizontal position and opens the butterfly valve B'.

Having now described my invention, what I claim as new, and desire to secure by Letters Patent, is—

1. In combination the casing having the inlet port, the valve therefor, the cross plate C, the overflow pocket D, the discharge opening through the cross plate C, the lever connected with the valve, the device carried thereby and arranged in the overflow pocket to be operated by the rise of water in the

casing and the sill a' arranged to direct the water to the said pocket, substantially as described.

2. In a water meter the combination of a box such as A having pockets such as D and A^3 with the butterfly valve B' at inlet opening, the balanced beam such as E carrying regulating pan such as D' furnished with slide d' and orifice d and with the outlet open-

ing C preferably furnished with a slide such as C' substantially as herein described and as illustrated in my drawings.

In witness whereof I have hereunto set my hand in presence of two witnesses.

GEORGE CHAFFEY.
